VISCOMETER

Elmer H. Payne, Wood River, Ill., assignor to
Standard Oil Company, Chicago, Ill., a corpora-
tion of Indiana

Application December 31, 1935, Serial No. 56,969

4 Claims. (Cl. 265—11)

This invention relates to viscometers and, in particular, to improvements in viscometer tubes of the type used in the Saybolt instrument, in which the upper end of the tube extends into a cup forming an overflow channel and thus accurately determining the height of liquid in the tube.

In making viscosity determinations by the official A. S. T. M. Saybolt universal and/or Saybolt furol viscometers, the viscometer tube is filled until the oil overflows into the overflow cup and floods the end of the tube, and the oil brought to the desired temperature in a constant temperature bath. After the temperature of the oil in the oil tube has been constant for one minute at the desired temperature the surplus oil from the overflow cup and channel surrounding the end of the tube is removed by means of a pipette and/or suction line. In withdrawing the excess oil from the overflow cup great care must be exercised to avoid touching the rim of the viscometer tube while removing the excess oil from the overflow cup. This precaution is necessary for it has been determined that large discrepancies occur in the viscosity determinations when the rim of the tube is touched while removing the excess oil from the overflow cup because the meniscus of oil is disturbed thereby and the oil level is lowered. Due to the relatively small size of the overflow cup it is difficult for the operator to avoid touching the overflow rim with the pipette or suction tube.

It is an object of this invention to provide means for removing excess oil from the overflow cup of Saybolt universal and/or Saybolt furol type viscometers which removes the danger of touching the overflow rim of the viscometer tube while withdrawing excess oil from the overflow cup.

It is another object of this invention to provide a more rapid and efficient means of draining the overflow cup of Saybolt universal and/or Saybolt furol type viscometers.

A further object of this invention is to provide a rapid and efficient means of draining the overflow cup of Saybolt and/or Saybolt furol type viscometers without the necessity of inserting a pipette or suction tube in the overflow cup and frequently damaging the rim of the tube.

Other objects and advantages of this invention will become apparent from the following description read in conjunction with the accompanying drawing.

The figure in the accompanying drawing, which forms a part of the specification, is a vertical sec-

tional view of a Saybolt viscometer showing a preferred embodiment of the invention.

Referring to the drawing a standard oil tube 10 is provided at its lower end with a casting 11 which extends through the bottom of a constant temperature bath 12 and is secured thereto by nut 13. Casting 11 is provided with a large bore 14 and a smaller threaded bore 15 into which is screwed a Saybolt universal or Saybolt furol tip 16. The large bore 14 in casting 11 is plugged 10 by means of cork 17.

The upper portion of oil tube 10 terminates in an overflow rim 18 and is surrounded by an overflow cup 19 the bottom of which is slightly below the overflow rim 18. The trough formed by the 15 side of oil tube 10 extending above the bottom of the overflow cup 19, the bottom of the overflow cup 19 and the wall of the overflow cup 19 is termed "gallery" 20.

The overflow cup 19 is provided with a drain tube 21 which extends through bath 12 to a point 20 just above the bottom thereof. The lower end of drain tube 21 terminates in fitting 22 which extends through the bottom of constant temperature bath 12 and is secured thereto by means of nut 23 or other suitable means. The projecting end of fitting 22 may be plugged by means of cork 24. If desired the drain tube 21 may be extended through the bottom of the bath 12 and closed by a valved means such as a stop cock. The entire viscometer tube and the drain tube 30 are surrounded by a constant temperature bath 12 maintained at the desired temperature by suitable thermostatic control means.

In operation corks 17 and 24 are inserted in their respective fittings and the oil tube 10 filled with the oil to be tested until the same overflows the overflow rim 18 and fills "gallery" 20. After the oil in the tube has reached the desired constant temperature the cork 24 is removed from fitting 23 and the "gallery" 20 drained of oil. The instrument is now ready for the viscosity determination.

Through the expedient of my invention the excess oil is removed from the "gallery" in a rapid manner, and errors due to the overflow rim being touched by the pipette as is now being used, are eliminated, thereby resulting in more accurate and consistent viscosity determinations.

In the preferred embodiment of my invention I have shown the drain tube extending through the constant temperature bath so that the drain tube will be maintained at the temperature of the bath to facilitate the drainage of viscous oils and asphalts. However, the drain tube may be 55

made to extend from the overflow cup outside of the constant temperature bath without departing from the spirit of the invention.

Although I have described my invention in connection with Saybolt universal and/or Saybolt furul type viscometers, my invention is not limited thereto but may be exercised in connection with other viscometers requiring drainage from overflow cups. Further, while I have disclosed a specific embodiment of my invention in detail, changes in structure may be made without departing from the spirit of the invention. I therefore do not intend to be limited in the scope of the invention except as defined in the appended 15 claims.

I claim:

1. A viscometer comprising a viscometer tube, said viscometer tube being provided at its upper end with an overflow cup, said overflow cup having a drain tube extending downwardly from the bottom thereof and a constant temperature bath, said bath enclosing and surrounding said viscometer tube and said drain tube.
2. In a viscometer comprising a viscometer tube for receiving liquid to be tested, an overflow cup at the upper portion of said viscometer tube for receiving excess liquid from said viscometer tube and means for maintaining the oil in said viscometer tube at a constant temperature, the improvement which comprises providing said overflow cup with a drain tube, said drain tube extending downwardly from the bottom of said

overflow cup and completely enclosed by said constant temperature means.

3. In a Saybolt viscometer comprising an oil tube for receiving oil to be tested, a small bore tip secured to the lower end of said oil tube, an overflow cup surrounding the upper portion of the oil tube and extending slightly below the upper edge of said oil tube, and a channel formed by the side of said oil tube extending above the bottom of said overflow cup and the wall of said overflow cup for receiving excess oil from said oil tube and a constant temperature bath surrounding said viscometer, the improvement which comprises providing the bottom of said constant temperature bath with a recessed well and providing said overflow cup with a drain tube communicating with the bottom of said overflow cup and said recessed well in the bottom of the constant temperature bath whereby said channel is drained of excess oil.

4. A viscometer comprising a viscometer tube, said viscometer tube being provided at its upper end with an overflow cup, a constant temperature bath enclosing and surrounding the viscometer tube and a major portion of the overflow cup and being provided with a recessed well in the bottom thereof, said overflow cup having a drain tube extending downwardly from the bottom thereof and communicating with the recessed well in the bottom of the constant temperature bath whereby the drain tube is maintained at a uniform temperature throughout its entire length.

ELMER H. PAYNE.
